DESIGN.

H. FINEGOLD.

LACE,

APPLICATION FILED SEPT. 8, 1916.

49,923.

Patented Nov. 21, 1916.

Inventor:
Harold F. Finegold.

UNITED STATES PATENT OFFICE.

HAROLD FINEGOLD, OF NEW YORK, N. Y., ASSIGNOR TO FELDMAN-GARFIELD CO., INC.,
OF NEW YORK, N. Y., A CORPORATION OF NEW YORK.

DESIGN FOR LACE.

49,923.

Specification for Design.

Patented Nov. 21, 1916.

Application filed September 8, 1916. Serial No. 119,135. Term of patent 3½ years.

To all whom it may concern:

Be it known that I, HAROLD FINEGOLD, a citizen of the United States, residing at No. 17 East One Hundred and First street, in the borough of Manhattan, city, county, and State of New York, have invented a new, original, and ornamental Design for Lace, of which the following is a specification, reference being had to the accompanying drawing, forming part thereof.

The figure is a view of a portion of a strip of lace, showing my new design.

I claim:

The ornamental design for lace as shown.

HAROLD FINEGOLD.

Witnesses:

JOSEPH FELDMAN,
ALVIN A. GOLDSMITH.
